UNITED STATES PATENT OFFICE

JOHN W. MOORE, OF GROSSE POINTE VILLAGE, DETROIT, MICHIGAN

LIQUID DISPENSING DEVICE

Application filed March 20, 1929. Serial No. 348,523.

This invention relates to liquid dispensing devices, particularly to that type of such devices from which beverages may be withdrawn in an automatic or semi-automatic manner.

More specifically, this invention is concerned with a dispensing apparatus which, upon the insertion of a coin in a slot and the manual manipulation of a handle or the like, will automatically place a receptacle in a receiving position measure out a predetermined quantity of liquid, and thereafter discharge the latter into the receptacle.

On the accompanying drawings; Fig. 1 is a rear elevation of the device with the cover therefor removed, showing the arrangement of the operating mechanism in normal position (full lines) and in measuring position (dot and dash).

Fig. 2 is a partial view in front elevation of the opposite side of the apparatus shown in Fig. 1.

Referring now to the drawings, wherein like reference numerals designate like parts throughout the several views, 6 indicates a plate formed of any desired material and upon the front and rear faces of which the entire operating mechanism is preferably mounted.

A manually operable lever 8, which will hereafter be referred to as the initiating lever, is pivoted intermediate its ends as at 9 on the rear of the plate in slightly spaced relation thereto. One end of this lever projects outwardly through a slot 10 in casing 7 and includes a finger ring 11. The opposite end of the lever extends inwardly and is shaped to provide an arcuate lug or extension 12. A pin 13 is fixed in the path of the lever to check its upward oscillation. The mechanism to be actuated by the initiating lever will now be described.

A normally horizontal lever 14 is mounted to oscillate at one end on a fixed pivot 16. Its opposite movable end has an upright link

member 17 freely pivoted thereto at 18. Above this link and near the top of the plate a circular disc 19 is rotatably mounted on a horizontal stud 20. Disc 19 has a radially extending arm 21 the end of which is pivotally connected with link 17 by a pin 22.

An upright lever 23 has its lower end freely pivoted intermediate the ends of lever 14 as at 24 and its upper end free to oscillate between the arms of a guide member 26 of any suitable form. Lever 23 is provided with an incision which terminates in an arcuate recess 27 of the same general size and shape as the contour of lug 12 on the initiating lever. A flat spring 28, secured to the recessed side of the lever as at 29 always engages a portion of lug 12 and may or may not prevent the engagement of lug 12 with recess 27, as will later be described. In the full line position shown, the moment of the inner end of lever 8, aided by the resultant force exerted by lever 23 when its spring 28 is held against lug 12 by the action of gravity, should be sufficient to maintain the upper end of lever 8 in contact with pin 13. However, a coiled tension spring (not shown) may be utilized, if desired, to more positively throw the lever 8 into its full line position.

Adjacent the inner side of lever 23 is a guide for the insertion of a coin C. This guide is formed by depressing a rectangular portion 29 of the plate 6 rearwardly through a distance at least equal to the thickness of the coin to be inserted, and thereafter cutting a vertical slot 30 through the material which joins the plate with the lower edge of the depressed portion. It will thus be seen that a coin may be pressed flatwise against the front face of the depressed portion (see Fig. 2) and thereafter permitted to drop through slot 30 to the rear side of the plate. A dog 31, substantially parallel to lever 23, is mounted on a fixed pivot 32 intermediate its ends. A tension spring 33 tends to oscillate the dog, which oscillation is checked at a predeter-

mined point by a stop lug 34. The upper end of the dog is disposed adjacent to and below the coin slot and is provided with an inset surface 36 for engaging the periphery of the coin, a shield or guide member 37 for guiding the coin and maintaining it in the plane of insertion, and a shoulder 38 for limiting the downward movement of the coin. When there is no coin between lever 23 and dog 31, it will be seen that, flat spring 28 having sufficient resistance, the lug 12 cannot, by manipulation of lever 8, be caused to enter arcuate recess 27. The lug will merely slide over spring 28 and pass the recess and oscillate lever 23 independently of the other elements. However, when a coin is in place (as shown in full lines) and in resilient engagement with the lever 23 and dog 31, spring 33 being stronger than flat spring 28, the latter spring is flexed by lug 12 when lever 8 is manually oscillated and the lug enters recess 27, thereby lifting lever 23. The upward movement of lever 23 oscillates lever 14 which in turn rotates disc 19 through link 17 and disc arm 21.

The disc 19 is provided with peripheral teeth 39. A rotary valve 40 of any selected conventional construction is mounted just above disc 19 in a liquid supply line 41. The plug 42 of this valve carries a cog wheel 43 which meshes with the teeth 39 of disc 19, from which it results that the valve is operated by the disc. This valve is normally closed (full line position of mechanism) and is opened when the mechanism is actuated in the manner set forth in the preceding paragraph. Pipe line 41 receives a liquid, such as ginger ale under high pressure, and conveys it, when valve 40 is open, into a closed measuring tank 44. The lower end of this tank opens into a discharge valve 46 of the same general construction as valve 40. Its rotary plug 47 carries an operating arm 48, which arm projects into the path of a pin 49 on link 17 to be positively actuated thereby. A tension spring 50 resists the actuation of the arm and tends to retain it in normal full line position, in which position the discharge valve is open. A discharge pipe 51 conveys the liquid from valve 46 to a drinking receptacle in a manner later to be described.

A tension spring 52, secured to link 17 as at 53 and to the plate 6 as at 54, tends to maintain link 17, and hence the entire mechanism thus far described, in its full line position. At the upper end of link 17 a bracket 56 is mounted to carry a roller element 57. This element necessarily travels in a fixed path when the initiating lever is operated, and a locking member 58 is arranged in this path on a pivot 59. A spring 60 resiliently holds locking member 58 in engagement with a stop pin 61. The lower portion of the locking member is provided with a recess 62 shaped to receive and latchingly hold the

roller element 57 on link 17, when the latter reaches the upper limit of its path. The locking member is provided with a tripping extension 63, which, when lifted, will release the roller element and permit it to be drawn 70 downwardly by spring 52. Extension 63 has a slot 64 which permits the locking element to be oscillated about its pivot 59 without engaging a vertical guide rod 66 which is mounted centrally of the measuring tank 44. 75

Within the measuring tank a float 67 is arranged and provided with a central vertical bore for receiving the guide rod 66. This float may be made hollow or of solid impermeable material, but in either event its 80 specific gravity must be such that it will rise when liquid to be dispensed is caused to enter the tank by way of pipe 41. Slidably mounted on the guide rod above the float is an externally threaded sleeve 68 which in turn 85 receives an internally threaded bushing 69. It will be seen that as float 67 rises it will force the sleeve and bushing upwards to cause the latter to strike the tripping extension 63 and lift it. A lock nut 70 is threaded 90 on sleeve 68 so that the combined length of the sleeve and bushing may be adjusted and set to any desired value, thus to regulate the amount of liquid which may enter the tank before tripping the locking member and releasing the mechanism held thereby.

Horizontally disposed adjacent the upper side of the disc 19 and parallel thereto is a horizontally movable bar 71. One end of this bar is slidably received in a guiding bracket 100 72 and the other end is bifurcated and carries a vertical bolt and nut structure 73. A member 74 is secured on the vertical bolt within the bifurcation of the bar and projects forwardly through a horizontal slot 76 to the 105 front side of plate 6. The slot 76 is of sufficient length to permit the member 74 to move longitudinally thereof as the bar is reciprocated. Near its bifurcated end the bar 71 is provided with a stud 77 which, on the side 110 adjacent the disc, provides a pivot for one end of an actuating link 78 which is parallel to the bar 71. The free end of this actuating link is shaped on its under side to provide an arcuate recess 79 and a cam 80. A short 115 pin 81, upon which link 78 rests, is mounted near the periphery of the inner side of the disc. Said pin normally engages cam 80 and is adapted to slide off said cam into recess 79 when the disc is oscillated by the operating mechanism in the manner already described. During such oscillation the pin 81 cooperates with the recess to force link 78, and hence bar 71 and member 74, to the left (Fig. 1). When member 74 has about traversed the length of slot 76 another pin, 82, also carried by the disc closer to its periphery than pin 81, and spaced from pin 81 a distance substantially equal to that between recess 79 and cam 80, engages the cam 80 to 125 130

lift the corresponding end of the link and remove the recess from engagement with pin

81. When this happens a spring, embodied in the cup dispenser presently to be referred to, thrusts bar 71 and link 78 back toward their original positions.

Operation

The device is set up with its pipe 41 connected to a source of liquid supply and with its front face exposed to the view of thirsty and prospective customers. When a customer inserts a proper coin in the slot and throws the lever 8 from its full to dotted line position, he need but wait for a moment and without further effort a drink will be served.

Lug 12 of lever 8 presses flat spring 28 inwardly, engages recess 27 and lifts the elements 23, 14, 17 and 57 upwardly until roller 57 is received by, and latched within, recess 62 of locking member 58, as shown in broken lines in Fig. 1. Simultaneously the coin is rolled upwardly along dog face 36 by lever 23 and reaches its dotted line position at the same moment that roller 57 becomes latched, at which time, due to the resilient action of spring 33, the coin is ejected through a horizontal slot 96 in the lower end of lever 23, to a suitable receptacle in the bottom of the casing 7. As link 17 is moving upwardly its lug 49 strikes lever 48 and closes valve 46 against the action of spring 50, and its upper end rotates disc 19. During the first part of the rotation of disc 19 its pins 81 and 82 cooperate with recess 79 and cam 80 to cause bar 71 to operate the cup mechanism and deposit a cup. At the same time the disc begins to open valve 40 and as it reaches its final dotted line position it has caused the valve 40 to become fully opened. Now, with the parts in the positions just attained, the beverage flows through valve 40 into measuring chamber 44 and causes the float 67 to rise until, when exactly one cupful of liquid has entered the chamber (predetermined by adjustment of sleeve 68 and bushing 69), the bushing 69 is forced into tripping contact with extension 63 to oscillate locking member 58 about its pivot 59. This oscillation causes roller 57 to be suddenly disengaged from recess 62 and the mechanism to be drawn, with a snap action, back into its full line position by spring 52, at the same time quickly closing supply valve 40 and permitting the opening of discharge valve 46 by the action of spring 50. The cupful of beverage within the measuring chamber is now permitted to flow into pipe 51 and thence into the discharged cup. The drink has been served and the machine is now ready to perform another cycle of operation.

It will be understood that the device of this invention may be subjected to operation by a

vendor or attendant independent of the coin control.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What I claim as my invention is:

1. In a liquid dispensing device, the combination of a liquid supply tank, valve mechanism controlling the supply flow of liquid to said tank and the discharge flow therefrom, an initiating lever, an actuating lever having a resilient portion opposed to said initiating lever, said resilient portion permitting swing of said initiating lever independently of bodily movement of said actuating lever when said actuating lever is unrestrained, said actuating lever forming one wall of a passageway for receiving a deposited coin for engaging with and restraining said actuating lever, means controlled by said resilient portion for interlocking said actuating lever with said initiating lever whereby said initiating lever will bodily move said actuating lever when said actuating lever is restrained, and an operating chain between said actuating lever and said valve mechanism.

2. In a liquid dispensing device, the combination of a supply tank, valve mechanism controlling the flow to and from said tank, an initiating lever, an actuating lever connected with said valve mechanism, a spring controlled latch normally preventing operative movement of said actuating lever by said initiating lever, coin controlled means cooperating with said actuating lever to cause said spring controlled latch to permit operative connection between said levers whereby said actuating lever and said valve mechanism will be operated, said actuating lever having a coin release passageway therethrough for the escape of coins after operation of said actuating lever.

3. In a liquid dispensing device, the combination of a fluid supply tank, valve mechanism controlling the flow to and from said tank, an actuating lever, a connecting train between said actuating lever and said valve mechanism, an initiating lever, resilient latch mechanism between said levers normally resisting operative connection between said levers, and a dog adjacent said actuating lever, there being a passage between said actuating lever and said dog for receiving a coin for engaging with and restraining the movement of said actuating lever whereby said latch mechanism will yield and said initiating lever when actuated will operatively engage with

and move said actuating lever and the valve mechanism controlled thereby.

4. In a liquid dispensing device, the combination of a fluid supply tank, valve mechanism controlling the flow to and from said tank, an actuating lever, a connecting train between said actuating lever and said valve mechanism, an initiating lever, resilient latch mechanism between said levers normally resisting operative connection between said levers, and a dog adjacent said actuating lever, there being a passage between said actuating lever and said dog for receiving a coin for restraining the movement of said actuating lever whereby said latch mechanism will yield and said initiating lever when actuated will operatively engage with and move said actuating lever and the valve mechanism controlled thereby, said actuating lever when operated moving parallel with said dog and having an escapement passageway for coins.

5. In a dispensing device, the combination with dispensing means, of an actuating lever therefor, an initiating lever, resilient latch mechanism between said levers normally resisting operative connection between said levers, a dog adjacent to said actuating lever forming a passageway therewith for receiving a deposited coin, said dog serving to support a deposited coin against said actuating lever for restraining the movement thereof whereby said latch mechanism will yield and said initiating lever when actuated will operatively engage with and move said actuating lever, said actuating lever having a release passageway therethrough for escape of a coin after operation of said actuating lever.
